Primary Examiner — Susan Moon Lee(74) *Attorney, Agent, or Firm* — Foley & Lardner(57) **CLAIM**

We claim the ornamental design for a scanner, as shown and described.

DESCRIPTION

FIG. 1 is a top, front, left perspective view of a scanner;
 FIG. 2 is a left side elevation view thereof;
 FIG. 3 is a right side elevation view thereof;
 FIG. 4 is a front elevation view thereof;
 FIG. 5 is a rear elevation view thereof;
 FIG. 6 is a top plan view thereof; and,
 FIG. 7 is a bottom plan view thereof.
 Broken lines and unshaded portions contained within broken lines are not claimed.

1 Claim, 5 Drawing Sheets---
